Inventor:
John E. Cryer

UNITED STATES PATENT OFFICE.

JOHN E. CRYER, OF PEORIA, ILLINOIS.

JOINER'S BENCH.

Specification of Letters Patent No. 24,102, dated May 24, 1859.

To all whom it may concern:

Be it known that I, JOHN E. CRYER, of Peoria, in the county of Peoria and State of Illinois, have invented a new and useful Improvement in Joiners' Benches for Jointing and Squaring Boards and other Lumber; and I do hereby declare that the following is a full, clear, and exact description thereof, reference being had to the accompanying drawings, and to the letters of reference marked thereon, and made to form a part of this specification.

My invention relates 1st to a device for adjusting and securing a movable jaw by means of which the lumber to be worked may be held rigidly in its proper place; 2d, to an adjustable rest or gage, by means of which the lumber to be worked may be jointed and squared to an even given width 20 as hereinafter specified and represented.

In reference to the accompanying drawings, Figure 1, is a perspective view showing the bench with all its parts arranged for operation. Fig. 2, is an end view showing specially the device for operating the movable jaw. Fig. 3, is a sectional front view, showing the adjustable gage; the device by means the same may be adjusted, the graduated scale and index.

(A) represents a frame work similar to a joiner's ordinary bench.

(B) is a movable jaw, made to correspond exactly with the jaw (d), which is permanently attached to the frame (A). The jaw (B) near either end is attached to the supports (c, c), which are secured in their proper places by means of the sliding guides (e, e) extending longitudinally across the frame (A) and attached at either end to the bars (e') of the guides (e), is a rod (f).

(g) is a lever made to fit and work in slot (h) of the frame (A) and immediately below the top of said frame is formed with two arms (g') having in them slots (g'') through which the rod (f) is made to pass; the arms (g') of the lever (g) are pivoted to the cross piece (A') of the frame (A) as represented. So that, as the lever (g) is moved backward and forward, the supports

(c, c) will receive a corresponding motion, and the jaw (B) open or to contract as may be required.

Upon either side of the slot (h) of the frame (A) is a rack (k) into which the dog (l) of the lever (g) takes as said lever is 55 pressed backward, thereby securing the movable jaw (B) in any position required to hold the lumber, between the two jaws, (B, d).

(p) is an adjustable gage arranged between the jaws (B, d) in such manner as to support the board or other piece of lumber, to be wrought, the gage (p) rests at either end upon screw rods (r r), these rods (r r) pass down through the pinions (n n) which 65 are made to screw upon the rods (r r) and are secured in their places by means of clamps (s s).

(t) is a shaft provided near each end with worms (t') by means of which the pinions (n n) are made to operate.

(j) is an index attached to the screw rod (r) which by means of the graduated scale (m) enables the operator to adjust the gage, to the width required for the lumber 75 to be wrought.

The operation of the above described invention, may be described as follows, the gage (p) will first be adjusted in proper position with reference to width of the lumber required, this will be accomplished by turning the crank (v) of the shaft (t) and working the screw rods up or down as may be required, by means of worms (t') and pinions (n n). This being done, the piece of 80 lumber to be wrought will be placed upon the gage (p) and the lever (g) thrown back until the jaw (B) impinges tightly against the lumber and secures it between the two jaws, the dog (l) of the lever (g) taking into 85 the rack (k) secures this position, a plane provided with shoes or stops as shown in Fig. 1 is then used, until the shoes ride upon the edges of the jaws, the upper edges of the jaws being perfectly parallel with the upper edge of the gage, the board planed or jointed must be of an even width and precisely like each succeeding board passing through the same process.

What I claim as my invention and desire 100 to secure by Letters Patent is—

1. The movable jaw (B) constructed and arranged with reference to the permanent jaw (b) in such manner as to secure properly

the lumber to be wrought and at the same time to form a track or guide for the plane during the operation of jointing and squaring lumber, as herein set forth.

5. 2. Operating the jaw (B) by means of guides (e e') rod (f) lever (g) and dog (l) substantially as herein described.

3. The gage (p) adjustable vertically with reference to the jaws (B, b) in combination,

with the scale (m) substantially as and for the purposes set forth.

In testimony of which invention I have hereunto set my hand.

JOHN E. CRYER.
